UNITED STATES PATENT OFFICE

JOSEPH A. V. TURCK, OF WILMETTE, ILLINOIS, ASSIGNOR TO FELT & TARRANT MANUFACTURING COMPANY, OF CHICAGO, ILLINOIS, A CORPORATION OF ILLINOIS

CALCULATING MACHINE

Application filed April 30, 1929. Serial No. 359,263.

This invention relates in general to improvements in calculating machines having ordinal columns and transverse banks of keys for manipulation thereof, and more particularly to improvements in calculating machines of the multiple order key-driven type in which calculation is effected merely by depression and release of the individual keys of a plurality of columns and banks thereof that make up the keyboard of the calculating machine.

Objects of the invention are: to divide the keyboard of machines of the above noted types that have a large multiple order capacity into a multiplicity of sections for adding and accumulating a plurality of separate totals independently of each other on a single calculating machine contemporaneously from distribution sheets of different kinds; to provide for separating certain elected columns of keys from other columns by individually removable columnar cover plates which cover and prevent depression of the keys of the columns they are electively positioned over, but allow the accumulator wheels for the selected orders to act as overflow wheels for the carry over of tens for the orders lower than the respective selected orders that are covered, whereby the columnar cover plates may be shifted at will from one to another order independently of the other columnar cover plates and the number of uncovered columns of keys between each two adjacent columnar cover plates may be varied at the election of an operator; to provide for covering one or a plurality of banks of keys, such as banks of six to nine keys, at the election of an operator and to provide such covering of banks of keys by individually removable bank cover plates, whereby the number of columns to be covered by the bank covering plates may be varied at will to correspond with the number of columns set off between each two adjacent columnar cover plates; to provide such bank and columnar key covering plates which may be removed and attached to the keys without requiring depression of the keys which would, with some types of calculating machines effect a partial keystroke and thereby cause a locking of the entire keyboard; to pro-

vide bank and columnar key covering plates capable of the above noted advantages which will not become displaced or jarred off during rapid operation of the uncovered keys; to provide for such bank and columnar key covering with plates that are not unsightly to the eyes, and that furnish complete safety to an operator against scraping of the fingers on such plates or sharp edges thereof, and that will be in true alignment with the keys covered and will be positively held thereon; and the invention has for further objects such other advantages in construction and operation as may be found to obtain in structures and devices hereinafter described and claimed.

In the accompanying drawings, forming a part of this specification and showing, for purposes of exemplification, a preferred form and manner in which the invention may be embodied and practiced, but without limiting the claimed invention specifically to such illustrative instance or instances:—

Figure 1 is a top plan view of a calculating machine of the multiple order key-driven type showing the keyboard thereof and one arrangement of the bank and columnar cover plate devices thereon;

Fig. 2 is a right hand side elevational view showing the bank and columnar key covering plates in the position they assume when attached to the keys;

Fig. 3 is a vertical cross-sectional view taken on the line 3—3 of Fig. 2, showing a set of one of the bank covering plates having capacity for four ordinal columns of keys;

Fig. 4 is a vertical cross-sectional view taken on the line 4—4 of Fig. 3 showing one of the columnar cover plates in position over one ordinal column of nine keys;

Fig. 5 is a vertical cross-sectional view taken longitudinally of the orders of the machine keyboard on the line 5—5 of Fig. 3 and showing the position the bank cover plates assume when attached to the keys;

Fig. 6 is a bottom plan view, partly in section, taken on the line 6—6 of Fig. 4, showing the attaching position of one of the columnar cover plates with respect to an ordinal col-

umn of keys, the keys between the opposite end keys being omitted for clearness of illustration;

Fig. 7 is a top plan view showing one of the bank covering plates that has the ordinal capacity for all ordinal columns of the machine and that has the capacity for four banks of keys across the entire keyboard, and showing a plurality of some of the other columnar cover plates employed, for instance, with the bank covering plates shown in this figure of the drawings, each of said columnar cover plates extending over only the keys of their respective elected ordinal columns that are not covered by said bank covering plates.

In its present embodiment, the invention is incorporated in a calculating machine of the multiple order key-driven type, such as exemplified in the United States Letters Patent No. 1,072,933 to Dorr E. Felt, and others to said Dorr E. Felt, and also in United States Letters Patents 1,357,747, 1,357,748, 1,367,468 and others to the present inventor Joseph A. V. Turck. For convenience the ensuing description will be directed to this use of the invention. The novel features of the present invention are, however, readily susceptible of other valuable application, for example, with other types of adding or calculating machines, hence the invention is not confined to the specific use and specific embodiment herein described as an illustrative example.

Referring to the drawings, there are shown views of a key-driven calculating machine 10. The calculating machine comprises in its construction a lower casing 11 in which the actuating mechanism, accumulator mechanism, and zeroizing mechanism are contained, and a top casing plate 12 having a row of eight apertures 13 for reading the register numeral wheels 14. A multiplicity of ordinal columns 15 of nine keys 16 are provided, each ordinal column being companion to one of the numeral wheels 14. Each key 16 is provided with a stem 17 that extends through the top casing plate 12 and is adapted to actuate actuating mechanism beneath said plate upon each depression and release of its key 16.

50 The machine shown on the drawings is provided with a zeroizing manipulative device 18, a keyboard lock release key 19 and a keyboard and zeroizing lever lock 20.

For distribution and other statistical work, the keyboard is divided into separate keyboards by means of removable longitudinal division pieces or columnar key cover plates 21. Each such piece 21 is arranged to longitudinally cover a row or ordinal column of nine keys to set off one or more ordinal columns of keys between it and another such division piece mounted over another row of keys, and to prevent manipulation of the keys that they respectively cover, while allowing the accumulators and numeral wheels of their

respective orders to act as overflow wheels for the orders lower than their respective orders. These columnar cover plates 21 are constructed so as to be readily removable from the keys in order to be shiftable at will from one order to another independently of each other, and in order to allow for the normal use of the whole keyboard of the machine, by removal of the longitudinal columnar pieces 21 from the keyboard, when desired. The longitudinal columnar division pieces provided by the present invention are long cupped plates 21, each so constructed in size and length as to set down over any column of keys and cover the key buttons and their numbers from view. Certain of the longitudinal pieces 21 are made of sufficient length to cover an entire ordinal column of keys and others 22 are made in different lengths respectively of such length as to cover a plurality of keys in any one ordinal column but less than the entire column. For instance, some are adapted for covering two keys, others three keys, etc., in any one ordinal column. Each of the longitudinal columnar division pieces comprises a longitudinally extending top member 24 disposed in a single plane and having two oppositely disposed depending side flanges 25 extending continuously from one end 26 to the other 27 thereof. The side flanges 25 are rounded at 28 to provide a smooth surface that will not injure the fingers of an operator during movement of the fingers alongside or in contact with said pieces during manipulation of the uncovered keys between each two of said pieces. The side flanges 25 are spaced from each other a distance just sufficient to clear the sides 30 of the keys so as to prevent binding thereon and yet be sufficiently close to the sides 30 of said keys to maintain the pieces 21, 22 in alignment with the columns of keys when mounted thereon. In order that these longitudinal columnar division pieces 21, 22, may be held securely, but removably, in place, each end is provided with a rounded end 31 terminating in a turned-in ledge 32 spaced just sufficient distance from the top surface 24 so that one of the ledges 32 may project under the front edge of a lower numeral key button, for instance, the "1" key, and the other of the ledges 32 may project under the rear edge of a higher numeral key button, for instance, the "9" key, in one and the same ordinal column of keys. With this arrangement and construction, the longitudinal columnar division pieces 21, 22 may be and are assembled over an ordinal column of keys by hooking one of the ledges 32 over the front edge of one key and by hooking the other of the ledges 32 under the rear edge of another higher numeral key by springing the higher numeral forward just a slight amount which is enough to allow the ledge 32 at the rear of the particular piece 130

21, 22, to drop over and under the higher numeral key so that when pressure is released on said key it will spring back to the position shown in Figs. 1 and 4 with the lower edge of the key button over the ledge 32.

5 As the type of work usually performed on the keyboards so apportioned off on a single keyboard by the longitudinal columnar division pieces 21, 22, is of addition of the kind 10 which permits of the employment of the system generally known as the "double touch" system which requires only the use of keys from 1 to 5, it is an advantage to also have the higher numeral keys of the keyboard 15 blocked off in banks. Thus plates 33 similar in construction to the plates 21, 22, are provided to cover banks of keys, in addition to the covering of elected columns of keys. As shown, the plates 33 are adapted to cover 20 banks of all keys above the "5" numeral keys.

As plates 33 of various columnar capacity and of various bank capacity are required in view of the varying requirements incidental to the types of distribution and statistical 25 work that the machine is to be used for, a plurality of plates 33, respectively of different columnar and bank capacities are provided, some like 34 adapted to cover all of 30 the keys above the "5" keys of all orders of the machine, and others like 35 of different widths, respectively of such width as to cover banks of keys in a plurality of orders but less than the entire ordinal capacity of the machine. The number of columns covered 35 by the plates 35 is, however, not a specific feature of the invention, since a set of said plates but of different columnar and bank capacities is provided. As each of the plates 33 of the set are substantially alike in construction and differ from each other only in 40 ordinal capacity and in bank capacity, a showing of the plates of four ordinal capacity and four banks capacity, and a showing of the plates of four banks capacity and of ordinal capacity to cover all orders of the machine will be sufficient for an understanding of the present invention, and of the other plates 35 of the set which are of ordinal capacity of two, three, five, six, etc., ordinal 45 columns, and which have a bank capacity of two, three, five, six, etc., banks of keys. The bank covering plates 33, like the longitudinal division pieces, 21, 22, are constructed so as to be readily removable from the keys to permit of great flexibility in shifting them with respect to the various banks of keys and orders of the keyboard. The bank covering plates 34 and 35 are each constructed to set down over and cover and be removably attached to the keys in the same manner as are the longitudinal columnar division pieces 21. Each of the bank covering plates 34 and 35 comprises a top member 36 disposed in a single plane and having two oppositely 50 disposed depending front and back flanges

37 extending continuously along the front and rear of the pieces. The flanges 37 are rounded at 38 to provide a smooth surface that will not injure the fingers of an operator during manipulation of the keys of the keyboard. The flanges 37 are spaced from each other a distance just sufficient to clear the keys of the foremost and rearmost banks of keys of a plurality of banks of keys of the keyboard so as to prevent binding thereon 55 and yet be sufficiently close to the front and rear sides of the keys of the foremost and rearmost banks of keys when positioned thereon in order to maintain the pieces 34 and 35 in alignment with the banks of keys. In order that these pieces 34 and 35 may be held securely, but removably, in place, each flange 37 terminates in a turned-in lip 39 spaced just a sufficient distance from the top surface 36 so as to engage under the key buttons of the keys and an end ledge 32 under a key covered by a longitudinal columnar division piece. These plates 34, 35 are therefore attachable and removable in the same manner above set forth in the description of the longitudinal columnar division pieces 21. 60

The bank covering plates 35 that are intended for covering either the lowest or highest ordinal column of the machine are provided with a side flange 41 for enclosing the outermost sides of the keys in said orders and on the side opposite the flange 41 are cut away at 42 to fit around the sides of the longitudinal columnar pieces 21 and terminate 65 in a free edge 43 adapted to overlap the top of an adjacent columnar division piece 21, as shown in Fig. 1. The plates 35 that are intended to be used between other plates 35 for covering banks of keys between the other plates 35 are cut away on their opposite sides at 44 to accommodate similar longitudinal pieces 21, and terminate in free edges 45 adapted to overlap longitudinal columnar division pieces 21 at opposite sides of the respective plates, as shown in Fig. 1. 70

One manner of employment of the bank covering plates 35 is shown in Fig. 1, and another manner of employment of the bank covering plates is shown in Fig. 7. As shown 75 in Fig. 1, when it is desired to use only that portion of the keyboard which includes the "1" to "5" keys inclusive, a longitudinal columnar division piece 21 is placed over each of the 5th, 10th, 15th and 20th orders of the machine and a bank covering plate 35 having capacity for four ordinal columns of keys and for four banks of keys is placed over the "6" to "9" keys inclusive of the first to fourth orders, another is placed over the "6" to "9" 80 keys inclusive of the sixth to ninth orders, and similarly another over the eleventh to fourteenth and sixteenth to nineteenth orders respectively. 85

From the foregoing it will be apparent 90

that with a machine provided with a set of the removable longitudinal columnar division pieces 21, 22, and the removable bank covering plates 34 and 35, respectively having capacity for two to eight banks of keys and for two to, for instance, twenty ordinal columns, that the variation in size and arrangement of the keyboards is practically unlimited. For example, by employing the bank covering plate 34, there may be provided a keyboard having only five numeral keys in each order, and by employing the longitudinal division pieces 22, such keyboard of only five numeral keys may be readily converted into a two column keyboard by placing one of the division pieces 22 on the tenth ordinal column; three keyboards, by placing division pieces 22 on the seventh and fourteenth columns; four keyboards by placing division pieces 22 on the fifth, tenth and fifteenth columns; and in like manner, other keyboards up to two column capacity can be readily arranged. By employing the bank covering plates 35 and the longitudinal division pieces 21, or 22, a like subdivision may be made, and the number of banks of keys covered in one keyboard may be greater or less than those in an adjacent or remote keyboard on the main keyboard, i. e., viewing Fig. 1, the first keyboard may have the "6" to "9" keys covered, the second keyboard may have the "5" to "9" keys covered, and the third keyboard may have the "4" to "9" keys covered, and the fourth keyboard may have the "3" to "9" keys covered. As shown, the bank covering plate 34 has its two oppositely disposed sides terminating in depending flanges 48 to enclose the sides of the outermost columns of the machine, but of course, if desired, such flanges may be omitted without detracting from the inherent advantages of such plates.

As an advantage to an operator in taking distribution items from distribution sheets in bookkeeping and other types of office work, when records are to be compiled and added, provision has been made for inserting and holding legends of different types of distribution that the keyboard is subdivided for. As shown in Fig. 1, each of the plates 33, 35, are provided with card retainers 46 having lips 47 for removably holding a legend-bearing card in position over each of the columns of keys set off by the columnar division pieces. The invention as hereinabove set forth is embodied in a particular form of construction but may be variously embodied within the scope of the claims hereinafter made.

I claim:

1. In combination with a calculating machine having a keyboard comprising parallel rows of finger keys with buttons thereon, a columnar covering plate mounted over and obscuring the buttons of a plurality of keys in one of the rows thereof and visually

and physically setting off the keyboard into separate simultaneous keyboards, and means for removably clipping said plate to the underside of the buttons of the keys, whereby said plates may be shifted from row to row at will to vary order and numbers of rows of keys that may be selected for setting off as separate keyboards by said plate.

2. In combination with a calculating machine having a keyboard comprising parallel rows of finger keys with buttons thereon, a columnar covering plate mounted over and obscuring the buttons of a plurality of keys in one of the rows thereof and visually and physically setting off the keyboard into separate simultaneously accessible keyboards, a separate bank covering plate mounted over the buttons of banks of the keys in the separate keyboards set off by said columnar plate and thereby obscuring and reducing the number of accessible banks of keys in the separate keyboards set off by said columnar plate, and means for removably clipping the columnar plates and the bank plates to the underside of the buttons of the keys, whereby said plates may be shifted at will to vary the order and numbers of keys that may be selected for setting off as separate keyboards by said plates.

3. A covering plate for obscuring the buttons of a row of finger keys on the keyboard of a calculating machine comprising a top member for covering and obscuring the tops of the buttons of a row of keys; depending side flanges integral with said top for enclosing the sides of the buttons that are on opposite sides of the row of keys covered by said top, said side flanges terminating outside the bottoms of said buttons; and flanges integral with and depending from said top for enclosing the outer portions of the buttons of the two keys at the end of the row of keys, said end flanges having inwardly bent holding lips for engagement with the bottoms of the buttons of the two keys at the opposite end of the row thereof.

4. A covering plate for obscuring the buttons of a row of finger keys on the keyboard of a calculating machine comprising a top member for covering and obscuring the tops of the buttons of a row of keys; end flanges integral with and depending from said top for enclosing the outer portions of the buttons of the two keys at the end of the row of keys, said end flanges having inwardly bent holding lips for engagement with the bottoms of the buttons of the two keys at the opposite end of the row thereof.

In testimony whereof I have hereunto set my hand.

JOSEPH A. V. TURCK
